UNITED STATES PATENT OFFICE.

NILS MILLER, OF PORTLAND, OREGON, ASSIGNOR, BY MESNE ASSIGNMENTS, TO
PORTLAND INDUSTRIAL COMPANY, A CORPORATION OF OREGON.

DOOR-HANGER.

1,253,509.

Specification of Letters Patent. Patented Jan. 15, 1918.

Application filed December 18, 1916. Serial No. 137,709.

To all whom it may concern:

Be it known that I, NILS MILLER, a subject of the King of Sweden, and a resident of Portland, in the county of Multnomah 5 and State of Oregon, have invented a certain new and useful Improvement in Door-Hangers, of which the following is a specification.

One of the principal objects of my invention is to provide an improved door hanger 10 of the lever type, by means of which the door is hung, free of rollers, runners, or other devices, in such manner as to be capable of movement into opening and closing positions along a constant horizontal line, 15 and with a minimum amount of exertion.

Another object of the invention resides in the provision of a door hanger of the class described, which is capable of such adjustment that the door will return automatically 20 to closed from open position.

A further object is to provide an improved door hanger of the nature set out, characterized by simplicity, durability, and economy in manufacture and maintenance.

With these and other objects in view, which will become apparent as the description proceeds, the invention resides in the construction, combination, and arrangement of parts hereinafter more fully described and claimed, and illustrated in the accompanying drawings in which like characters of reference indicate like parts throughout the several figures, of which—

Figure 1 represents a side elevational view of a door hanger constructed according to my invention, showing the same in operation, the door to which the hanger is connected being shown in half open position;

Fig. 2 represents a similar view, showing the hanger as adjusted for effecting automatic closing movement of the door;

Fig. 3 represents a sectional view taken vertically through the hanger;

Fig. 4 represents a view in perspective of the hanger;

Fig. 5 represents a side elevational view of the hanger, showing the arrangement when the hanger occurs alongside of the 50 door, the door being indicated in open position;

Fig. 6 represents a view of the arrangement when the hanger is placed alongside the door, the door in Fig. 6 being indicated 55 in half closed position.

Referring more particularly to Figs. 1 to 4 inclusive, in which the hanger is shown arranged above the door, it will be observed that I suspend the door, indicated at 5, from the spaced arms 6 by means of brackets 7 60 secured to the upper portion of the door, and pivoted at 8 to the lower ends of the arms. The arms 6 are in turn suspended from a parallelogram which consists of the lower bar 9, secured by fastenings 3 extending through openings 4, to the wall of the building in which the door opening is formed; the upper bar 10, parallel with the lower bar and spaced from it; and the end bars 11 which are parallel with each other 65 and which are pivotally connected at their opposite ends to the bars 9 and 10 at the points 12 and 13 respectively. The upper ends of the arms 6 are pivotally connected to the upper bar 10 of the parallelogram or 70 wall section as it may be called of the hanger, at the same point 13 on which the end bars 11 are pivoted. Preferably the upper ends of the bars 11 and arms 6 are offset toward each other, as indicated in the 75 drawings, to provide ample clearance between the elements.

Arranged midway between and parallel with the bars 11, is a lever 14 pivoted at its lower end on the bar 9 at the point 15, and at 80 a point removed from its upper end, to the upper bar 10 at 16. The portion of the lever 14 above the bar 10 is bent or inclined at a proper angle, determined by experiment, toward one of the arms 6, and a link 90 17 connects the upper inclined portion 18 of the lever with the arm 6 toward which this portion is inclined. The link is pivoted at one end at point 19 to lever 14, and adjacent its other end is provided with a 95 series of openings 20 adapted to be selectively passed over the bolt 21 carried by arm 6 for pivotally connecting the link with said arm. The ratio of the distances between points 13 and 21 and 19 and 16, as determined by experiment, is such that, when the bolt 21 is in the central or neutral one of the series of openings 20 the door in being shifted from closed to open position and vice versa, maintains a constant level and 100 traverses a constant horizontal path, the arms 11 and 6, moving at an equal rate of speed so that the bisector of the varying angle described by either pair of these arms is always perpendicular. This is illustrated 105 110

in Fig. 1, in which the dotted line position of the parts illustrates the position assumed when the door is in full open position, the full line position being that which is assumed when the door is in half open position.

It will be understood, of course, that the hanger is applicable to doors which move either to the right or to the left in opening, 10 and the principle of action of the parts is exactly the same in either case. This action may be briefly described, by way of illustration, with reference to Fig. 1. Here, when the door moves from full line to dotted line 15 position, the movement of the arm 6 to which the link is connected, in swinging on its pivot, is imparted by a pull through the link 17 and lever 14 to the bar 10 and arms 11, swinging the latter over on their pivot 20 12 at a rate of speed equal to the movement of the arms 6. When the door is shifted from dotted to full line position, a push is imparted through the link and lever to the arms 11, moving them in a reverse direction, 25 and at a rate of speed equal to the movement of arm 6, as will be understood.

When it is desired that the door return automatically to closed, from open position, the link 17 is so adjusted with relation to the 30 arm 6 to which it is connected, that the bolt 21 passes through one of the series of openings occurring on one side or the other of the central or neutral opening. In Fig. 2, the arrangement is such that the door is moved to the left in being opened, and automatically returns to closing position, moving toward the right to assume closed position. In this instance the bolt 21 passes through the outermost of the series of openings 35 20, and as the door is shifted toward the left, the arm 6 will move gradually upwardly about their pivots 13, and will thus bodily lift the door as it is swung toward the left in being opened, so that when the door is released from its open position it will automatically, by action of gravity, swing back toward the right into closed position. When the hanger is applied to a door which is moved to the right in being opened, and 40 45 it is desired to have the door move automatically into closed position, the bolt 21 is passed through the innermost one of the series of openings, or that one nearest the pivot point 19, so that when the door is shifted to the right, the arms 6 in moving to the right, will move upwardly about their pivots, and thereby bodily lift the door, so that when it is released it will automatically 50 55 shift into closed position.

In order that the hanger may be properly supported and guided in its movement, I 60 secure a guide strip 22 to the wall of the building, between which strip and the wall the lever 14 travels. This strip is arranged 65 adjacent the lower end of the lever, so as to

reduce the friction to a minimum, and the strip acts as a guide and brace for the hanger and also as a stop to limit the movement of the hanger in both directions.

The arrangement so far described refers 70 particularly to that one in which the hanger is arranged above the door as shown in Figs. 1 to 4 inclusive. When, however, by reason of the fact that there is not sufficient head-room or an obstruction occurs preventing the 75 arrangement of the hanger above the door, the construction shown in Figs. 5 and 6 may be resorted to. In these figures, the hanger is arranged alongside of the door, and the arrangement includes the arms 11^a pivotally 80 connected at their upper ends at points 12^a with brackets 23 secured to the wall above the door opening. The lower ends of arms 11^a are pivotally connected as at 13^a with a connecting bar 10^a, and the lever 14^a is likewise pivoted at 16^a to the bar 10^a, adjacent its lower offset end 18^a, the upper end of the lever being pivoted to a bracket which is also secured to the wall above the door, the pivot point of the lever and bracket being 90 indicated at 15^a. The arms 6^a are pivotally connected at their lower ends with the bar 10^a on the point 13^a, and at their upper ends are pivotally connected as at 8^a, see Fig. 5, with the door adjacent the upper edge of the 95 latter. The lever 14^a is connected by the link 17^a with one of the arms 6^a, toward which the portion 18^a of the lever is inclined. The operation of the parts in this instance is identical with that already described, and 100 it is thought therefore that a detailed description of the operation would be superfluous. Suffice it to say that the position indicated in Fig. 5 is that taken by the parts when the door is in open position, and that shown in Fig. 6 is the position when the door is half closed. It will be noted that, 105 in this arrangement, the arms 11^a may be formed of right angular strips of metal if desired, so that when the door is swung into 110 full open position as indicated in Fig. 5, the portions of the arms 11^a adjacent the door opening will lie in respective horizontal and vertical lines, so as not to obstruct the corner 115 of the door opening. The arrangement shown in Figs. 5 and 6 presents many advantages in hanging car doors and the like.

Although I have described the preferred embodiment of my invention, I may desire to make such changes in the construction, combination, and arrangement of parts thereof, as do not depart from the spirit of the invention and the scope of the appended claims.

I claim:

1. In a door hanger, the combination of a lower bar adapted to be secured to a support, parallel spaced arms rising from and pivoted to the said lower bar, an upper bar parallel with the lower bar and pivoted to 120

the upper ends of the said spaced arms, supporting arms of a length substantially equal to the length of the said spaced arms, said supporting arms being pivoted adjacent 5 their upper ends to the said upper bar at points coinciding with the points on which the said spaced arms are pivoted to the said upper bar, a lever arranged parallel with the spaced arms midway between them 10 and pivoted to the lower and upper bars, said lever having a portion extended beyond the upper bar and inclined toward one of the supporting arms, a link pivoted at one end to the extended portion of the lever 15 above the upper bar, an adjustable connection between the opposite end of the link and the supporting arm toward which the extended portion of the lever is inclined, and means for pivotally connecting the lower 20 ends of the supporting arms to a door.

2. A door hanger including a parallelogram comprising spaced parallel lower and upper bars, and spaced parallel arms pivoted to the lower and upper bars, the lower 25 bar of the parallelogram being secured to a support, spaced and parallel supporting arms pivotally connected at their lower ends to a door and pivoted adjacent their upper ends to the upper bar of the parallelogram, 30 a lever pivoted to the upper and lower bars of the parallelogram and having an extended portion inclined toward one of the supporting arms, and a link pivoted to the extended portion of the lever and also pivoted 35 to the arm toward which said extended portion is inclined.

3. A door hanger including spaced arms pivotally connected to a support, a bar extending between and pivotally connected to 40 the arms, supporting arms arranged in spaced and parallel relation and pivoted at one end to the bar and adapted to be pivoted at their other ends to a door, a lever arranged between the first said arms and pivoted 45 at one end to the support, the other end of the lever being extended beyond the connecting bar and inclined toward one of the supporting arms, and a link connection between the inclined portion of the lever 50 and the supporting arm toward which said inclined portion is bent.

4. A door hanger including a bar, arms pivotally connected at one end to the bar and at their other ends being pivotally connected 55 to a support, said arms being arranged in parallel relation, supporting arms pivotally

connected with the bar and arranged in parallel relation and adapted to be pivotally connected with a door, a lever pivotally connected to the support at one end and being 60 pivotally connected with the bar at a point intermediate the ends of the lever, and a connecting link having an adjustable pivotal connection with one of the supporting arms, said link being also pivotally connected 65 with the lever adjacent the free end of the latter.

5. A door hanger including a pair of spaced arms pivotally connected at one end to a support, means connecting the arms for 70 moving them in unison, supporting arms pivotally connected at one end to the said connecting means and adapted to be pivotally connected at their other ends to a movable object, a lever pivotally connected to 75 the support and to the said connecting means for moving in unison with the said spaced arms, and a connecting link crossing the said connecting means and pivotally connected to the lever and one of the supporting arms. 80

6. A door hanger including a parallelogram having spaced top and bottom bars, and spaced end bars, all of the bars of the parallelogram being pivotally connected together at their intersecting points, supporting arms pivotally suspended from the parallelogram and adapted to be pivotally connected to a movable object, one of the bars of the parallelogram being fixed to a support, a lever pivotally connected with the 90 fixed bar of the parallelogram and with the bar opposite the fixed bar, and a link pivotally connecting the lever and one of the 95 said supporting arms.

7. A door hanger including a parallelogram having spaced top and bottom bars and spaced end bars, all of the bars of the parallelogram being pivotally connected together at their intersecting points, supporting arms pivotally suspended from the 100 parallelogram and adapted to be pivotally connected to a movable object, one of the bars of the parallelogram being fixed to a support, a lever pivotally connected with the fixed bar of the parallelogram and with the 105 bar opposite the fixed bar, and mechanism actuated through movements of the lever for respectively causing the said spaced end bars and said supporting arms to be moved relatively in different angular relations on adjustment of said lever. 110
